UNITED STATES PATENT OFFICE.

EDWARD T. SCHOONMAKER, OF SOUTH ORANGE, NEW JERSEY, ASSIGNOR TO SARGENT & COMPANY, OF NEW HAVEN, CONNECTICUT, A CORPORATION OF CONNECTICUT.

DESIGN FOR A DOOR-KNOB.

No. 38,941.

Specification for Design.

Patented Dec. 10, 1907.

Application filed October 10, 1907. Serial No. 396,859. Term of patent 14 years.

To all whom it may concern:

Be it known that I, EDWARD T. SCHOONMAKER, of the town of South Orange, county of Essex, and State of New Jersey, have invented a new, original, and ornamental Design in a Door-Knob, of which the following is a specification, when taken in connection with the accompanying drawings, which form a part thereof, and in which—

Figure 1 represents a front elevation of a

door knob embodying my new, original and ornamental design, and Fig. 2 represents an end view of the same.

What I claim is;

The ornamental design for a door knob, as shown.

EDWARD T. SCHOONMAKER.
